OIL TUBE DRILL

Rudolf William Andreasson, Birmingham, Mich.

Application July 1, 1957, Serial No. 668,960

5 Claims. (Cl. 77—68)

This invention relates to an oil tube drill and has particularly to do with that type of drill in which a passage is provided within the drill to carry coolant to the drilling tip.

It has long been a problem to provide a proper drill for drilling oil holes in crank shafts, for example, or other deep, small holes. The problem of drill breakage is such that machines must frequently be reversed to avoid overloading or stopped for drill replacement.

The present invention contemplates the use of a drill which is formed from tubing in a manner in which the flute is straight-formed by crushing in the opposite sides of the tube, after which the fluted tube is twisted to provide the spiral shape, leaving passages within the tube in each spiral land. This type of tube, while successful for certain types of drilling in aluminum or brass, has been found to be weak for drilling steel or other hard metals.

It is an object of the present invention to utilize this inexpensive method of forming a drill and still provide a drill which is strong enough to accomplish its purpose. This is done by providing on the outside of the drill a hardened coating which has sufficient strength to rigidify the drill and prevent bending or twisting which will destroy the accuracy of the drill and also to provide the hard wearing surface, which is a further advantage.

It is another object to provide such a drill with a tip which is so adapted that it will provide a strengthening effect to the drill itself and prevent opening up which might otherwise occur in the shaped drill due to the dead-center action which tends to split a formed drill of this kind.

Another object of the invention is a provision for coolant access from the interior of the drill to the exterior of the tip.

Other objects and features of the invention having to do with details of construction will be apparent in the following description and claims.

Drawings accompany the disclosure, and the various views thereof may be described as:

Figure 1, an elevation of a completed drill with an applied shank.

Figure 2, a view of the tube from which the drill is formed.

Figure 3, the tube in progress of manufacture showing the straight flutes in general configuration.

Figure 4, the drill after being twisted.

Figure 5, a sectional view on line 5—5 of Figure 1.

Figure 6, an end view on line 6 of Figure 7.

Figure 7, an illustration of the manner in which the tip is assembled to the drill shank.

Figure 8, an enlarged view of the assembled end and shank.

The drill is preferably formed of a tube of hardenable steel shown at 20, such as SAE 1020-1030 steel, which can be surface hardened by a carburizing process. As shown in Figures 3 and 4, the opposite sides of the tube are fashioned together in a suitable die to create flute

2

portions 22 and leaving land portions shown generally at 24.

In the embodiment shown, the walls of the tube are brought together from opposite sides; and if desired, the inner apices of the flutes may be brazed together to provide additional strength. This, however, is not a requisite of the formation. The land portions consist of a margin 26 with relieved portions 28.

In Figure 4, the drill is shown in twisted helical form 10 wherein helical flutes and helical lands are provided. In twisting the body, the contacting portions of the web are brought in close relation, thus defining two independent passages in the drill body.

In the method of forming, the tube may be either 15 formed in cross section prior to twisting or twisted at the same time that the cross section is being rolled into it. After the drill body has been rolled to the proper shape, it will be seen that the passages within the tube resulting from the rolling operation are segmental in 20 shape as at 30, each passage forming in cross section substantially a segment of the circle. Thus, all available area within the tube is utilized for the passage of coolant.

When the tool body is completed, a suitable shank 40 25 is attached with suitable oil receiving holes, not shown, to co-operate with a fixture which provides oil and coolant. Prior to the attachment of the tool shank and the tool tip, which will be described in detail later, the formed shank is provided with a coating on its outer surface, which is materially harder than the shank itself. This coating can be provided in one embodiment 30 by a carburizing operation which hardens the surface of the tool to a considerable extent relative to the core. However, a preferred method and embodiment of fastening the shank of the drill is to provide it with a bonded coating, such as that disclosed, for example, in the United States Cole Patent 2,694,647, issued November 16, 1954.

The particular fuse coating which is preferred in connection with this treatment is a coating which has preferably extremely hard metals, such as tungsten carbide and chromium boride, but any use of the process disclosed in this patent which applies a relatively hard surface to the drill shank is contemplated.

Another process which can be used is that known to 45 the trade as "Colmonoy" coating, which is a coating of metal sprayed onto the shank. It has been found that applying a coating of this type, as shown at 50 in Figure 5, greatly increases the resistance of the tube against torsional distortion and bending. Drills so treated have been found to be very superior to drills otherwise formed; and in addition, they have a wearing quality against abrasion which is greatly increased over a normal drill shank.

Referring now to the tip construction, a tip 60 50 is shown in Figures 6, 7 and 8. This tip 60 is formed of a solid cutting tool steel or other equivalent material and is fluted at 62, each flute terminating in a cutting edge 64. The shank end of the tip is provided with a pair of dentate cusps 66 which engage recesses 68 formed in 55 the outer walls of the end of the drill shank (see Figure 7). These cusps are brazed into the drill shank along with the other contacting surfaces of the drill shank and the drill end. The combination provides 60 torque transfer at the outer walls which avoids a tendency to wedge open the drill.

The openings 30 65 may have their outlet through a surface recess 70 which is worked into the surface of the flute of the drill and to a depth that it will communicate with the segmental openings 30 when the drill end is joined, thus admitting egress and ingress of the coolant and lubricant.

With this arrangement, it is unnecessary to drill the cutting end of the device and the resulting combination of the elements is stronger and less expensive than a tool where internal drilling is required.

Another construction, shown in Figure 1, which may be used, is the utilization of a hole 80 on each land of the shank 20 just adjacent the tip 60. The coolant has an outward reaction which tends to lubricate the drill and float it away from the side walls of the hole on a film of liquid and the flow is then downward to the tip and back. The margin 26 with the relieved surface 28 forms a flow path for the coolant on the outer diameter of the drill to the cutting edges of the tip.

The steps in the making of the tool in résumé constitute first selecting a tube of proper steel as above indicated forming straight flutes in the tube with a shaped die, twisting the tube by a torsional application of force, cutting it to length, providing a coating of extremely hard material on the outside of the tube molecularly bonded to the surface thereof, and subsequently fashioning a cutting end and attaching the cutting end to the drill shank with a brazing operation or other equivalent.

The combination of the bonded coating and the carburizing process can be utilized also to obtain maximum resistance to torque and bending.

I claim:

1. A drill comprising a tube fashioned so that opposite parts of the tube will come into substantial engagement with each other leaving a lengthwise interior passage extending on each side of said engagement, said tube being fashioned into twisted helical form having spiral flutes and lands, and a drill tip secured at the end of the tube to receive a coolant from the passages within the tube, said tip having a plurality of cusp-like axial extensions on the end adjacent the tube to interengage axial recesses in the walls of said tube, means bonding the tip to the tube, said tip having flutes and lands which register with the flutes and lands at the end of the tube, the surfaces of the flutes of the tip being recessed inwardly adjacent the tube to communicate with the interior passages of the tube.

2. A drill comprising a tube fashioned so that opposite parts of the tube will come into substantial engagement with each other leaving a lengthwise interior

passage extending on each side of said engagement, said tube being fashioned into twisted helical form having spiral flutes and lands, and a drill tip secured at the end of the tube to receive a coolant from the passages within the tube, said tip having a plurality of cusp-like axial extensions on the end adjacent the tube to interengage axial recesses in the walls of said tube, means bonding the tip to the tube, said tip having flutes and lands which register with the flutes and lands at the end of the tube, the surfaces of the flutes of the tip being recessed inwardly adjacent the tube to communicate with the interior passages of the tube, and a thin, hard coating on all of the surfaces of said tube molecularly bonded thereto to create resistance to bending and torque stresses and to provide a hard wearing surface on said drill.

3. A device as defined in claim 2 in which the coating is that resulting from a carburizing process.

4. A device as defined in claim 2 in which the coating is a combination of a carburized surface and a molecularly bonded surface relatively harder than said tube.

5. A drill adapted to have coolant delivered to the cutting tip through internal passages which comprises a helical web portion formed by the walls of the tube squeezed together, the remainder of the drill body comprising helical lands on either side of flute passages formed by the walls of said tube surrounding passages parallel with said web portion, a separate, solid cutting tip affixed to said body, and openings in the walls of said tube on the ends of the lands adjacent the tip connecting said passages and the outer surface of said tip to permit coolant to flow out and around said tip and back through said flutes.
